United States Patent Office

Des. 239,822
Patented May 11, 1976

239,822

STATION WAGON

John C. Silva, Jr., Peabody, Mass.
(P.O. Box 1082, Saugus, Mass. 01906)

Filed Feb. 5, 1973, Ser. No. 329,628

Term of patent 14 years

Int. Cl. D12—08

U.S. Cl. D12—91

FIG. 1

FIG. 2

FIG. 3

FIG. 4

FIG. 1 is a front isometric view of the station wagon showing my new design.

FIG. 2 is a rear isometric view thereof.

FIG. 3 is a front elevational view thereof.

FIG. 4 is a rear elevational view thereof.

I claim:

The ornamental design for a station wagon, as shown.
